UNITED STATES PATENT OFFICE.

ALBERT E. SHARKEY, OF CUYAHOGA FALLS, OHIO, ASSIGNOR TO THE GENERAL RUBBER GOODS CO., OF CLEVELAND, OHIO.

COMBINED TOOL-POUCH AND TESTING DEVICE.

1,387,189.

Specification of Letters Patent. Patented Aug. 9, 1921.

Application filed March 6, 1920. Serial No. 363,696.

To all whom it may concern:

Be it known that I, ALBERT E. SHARKEY, a citizen of the United States, and a resident of Cuyahoga Falls, in the county of Summit and State of Ohio, have invented certain new and useful Improvements in Combined Tool-Pouches and Testing Devices, of which the following is a specification.

My invention relates to a combined tool pouch and testing device especially adapted for an electrician in the repair and testing of lines and apparatus.

It is a purpose of my invention to provide a device of the above described character which is of simple and inexpensive construction and which may be readily carried on the belt of a repairman in position to facilitate testing without removing the device from the belt, the tool pouch being also carried in convenient position to permit the ready insertion and removal of tools used in the repairing of electric apparatus.

I will describe one form of device embodying my invention, and will then point out the novel features in claims.

In the accompanying drawings:—

Figure 1 is a view, showing in front elevation one form of device embodying my invention;

Fig. 2 is a vertical sectional view of Fig. 1; and

Fig. 3 is a detail view, showing in side elevation one form of resistance coil embodying my invention when used.

Referring specifically to the drawings, in which similar reference characters refer to similar parts, the tool pouch or holder comprises a sheet 15 of suitable material, such as leather or the like, to the front side of which is secured, preferably by means of stitching, a sheet of similar material 16. As shown in Figs. 1 and 2, the sheet 16 is secured along its marginal edges to the sheet 15 in such manner as to cooperate with the latter to provide a pocket, the upper end of which is open to allow of the insertion and removal of tools to and from the pocket.

The sheet 16 is preferably molded into the shape shown prior to its application to the sheet 15 so that it is normally maintained in spaced relation to the sheet 15, as clearly shown in Fig. 2. The upper end of the sheet 15 is provided adjacent its vertical edges with upwardly extending projections 15^a to which are secured by means of rivets. 17

hooks 18. Each of the hooks 18 comprises a single length of suitable metal which is bent upon itself for a portion of its length to provide a hook which can be readily placed on the belt, and when in applied position to support the pouch in vertical position upon the same.

Secured to the rear side of the sheet 15, preferably by means of stitching is a sheet 19 of suitable material, such as leather or the like which is adapted to coöperate with the sheet 15 to form a housing for a testing device indicated generally at T. As shown in Fig. 3, the testing device T comprises a plate 20 of insulating material about which is wrapped a resistance wire 21 in such manner as to provide a multiplicity of turns that constitute a resistance coil. The opposite ends of the wire 21 are extended through openings 22 formed in the plate 20 adjacent the upper end thereof. The ends of the wire 21 are designated at 21^a, and fastened to these ends are leads 23 (Fig. 2) which are welded or otherwise permanently secured to terminal posts P. As shown in Figs. 1 and 2, the posts P are mounted within the sheet 15 at a point directly above the open end of the pouch, each post comprising a shank having flat heads 24 formed on the opposite ends thereof and confining the shank upon the sheet 15, as will be understood.

The wire 21 comprising the resistance coil, as well as the leads 23 are properly insulated throughout their lengths to prevent short circuiting of the coil. The testing device is designed for the purpose of locating short or open circuits and grounds and the testing is accomplished by making and breaking contact between the posts P and the wires of a line, in such manner that a spark will occur between the wires and the posts thus indicating that the line is intact. Of course, should no spark appear, it is an indication that the line is faulty in some respect.

Although I have herein shown and described only one form of combined tool pouch and testing device, it is to be understood that various changes and modifications may be resorted to without departing from the spirit of the invention or the spirit and scope of the appended claims.

Having thus described my invention, I claim:

1. A device of the character described comprising, a plate of insulating material,

a resistance wire coiled about said plate, a pouch for housing said plate and wire, terminal posts carried by the pouch and electrically connected to the ends of said wire, and 5 supporting hooks carried by said pouch.

2. A device of the character described comprising, a sheet of insulating material having extensions formed thereon, hooks

carried by said extensions, a second sheet of insulating material secured to the first sheet, 10 a plate of insulating material housed between the two sheets, a resistance wire coiled about said plate, and terminal posts carried by the first sheet and electrically connected to the ends of said resistance wire.

ALBERT E. SHARKEY.
